DESIGN FOR A DRESS

Elizabeth M. Ciccone, New York, N. Y.

Application December 2, 1938, Serial No. 81,504

Term of patent 3½ years

To all whom it may concern:

Be it known that I, Elizabeth M. Ciccone, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination of the specific dress disclosed of the specific embroidery on the yoke and sleeve portion, in combination with the stitched pleats on the lower portion of the waist and sleeves as shown.

I claim:

The ornamental design for a dress, substantially as shown and described.

ELIZABETH M. CICcone.
